SAFETY RAZOR

Application filed March 19, 1927. Serial No. 176,789.

My invention relates to safety razors and relates more particularly to improvements in that type of safety razor which is designed to have used therewith a flexible replaceable 5 steel blade and which is commonly known as the Gillette type of razor.

The Gillette type of safety razor is highly desirable because the blades can be replaced and a sharp blade always had at a small cost. 10 In these days of scant attire for women, they often employ a safety razor for shaving unsightly hair from the arm pits. It has been found dangerous, however, to use the average safety razor, whether the Gillette or other 15 types, because the sharp corners of the blade protrude sufficiently to cut the skin when contacting with a cupped or depressed area, such as the arm pit.

My invention is particularly useful for 20 shaving arm pits and other depressed or concave skin areas of the body without fear of injuring the skin. This invention employs the standard Gillette type of flexible steel blade and consists of a curved top member in 25 which the blade resides and a curved bottom or guard member for, in connection with the top member, giving the blade the desired curvature. The top member is so designed that it is impossible for the corners or ends 30 of the blade to contact with the skin area being shaven. A suitable screw handle assembly is, of course, provided.

In the accompanying drawing in which I 35 have illustrated a preferred embodiment of my invention and in which like reference characters refer to like parts,

Figure 1 is a top plan view of my improved razor,

Figure 2 is a side elevation thereof, with a 40 part in section taken along the line 2—2 of Figure 1,

Figure 3 is an inverted plan view of the razor,

Figure 4 is a side elevation of the top mem- 45 ber,

Figure 5 is an end elevation thereof,

Figure 6 is a side elevation of the bottom or guard member,

Figure 7 is a sectional view of the razor, 50 taken along the line 7—7 of Figure 3, and

Figure 8 is a plan view of the standard Gillette type of flexible steel razor blade.

Reference character 1 designates the curved body portion of the top or blade receiving member, which is provided with a screw-threaded shaft 2 and blade positioning studs 3. The blade receiving member is, in fact, shell-like, being cast from brass or other suitable metal with the shaft 2 and studs 3 integral therewith or it may be pressed out of sheet metal and have the shaft 2 and studs 3 welded or otherwise secured in place. The studs 3 act to position the blade and guard member. Obviously, the studs 3 are only desirable elements and are not necessary as shaft 2 will position the blade and guard member with respect to longitudinal movement and the shoulders 5 of the blade receiving member will position the blade and guard member with respect to lateral movement. From each end of the body portion 1, and integral therewith, extend semi-cup shaped shields or shield portions 4 so that the blade receiving member may be characterized substantially as an inverted gondola-like shell. I have shown the shields 4 as being semi-cup shaped so that a curved surface will always contact with all parts of the skin being shaven. It will be obvious, however, that these shields 4 may be made any desired shape, the purpose 50 of them being mainly to form a housing for the corners of the razor blade and to form a blade receiving member which will conform somewhat to the surface which it is intended to shave. The cup-shaped shields 4 also assist 55 in holding the lather that is gathered and accumulated from the shaven skin area by the blade. By reason of the shape and size of the shields 4, as shown for instance in Figures 2 and 4, shoulders 5 are formed 60 which, together with the shields 4, determine the effective cutting length of the blade to be used with my razor and also position both the blade and guard member against lateral movement.

The guard member consists of a curved body portion 6 to which may be secured, by welding for instance, the handle 7. From both sides, preferably, of the body portion 6 extend the guard prongs 8. From the ends 65

of the body portion 6 extend shorter and slightly heavier prongs 9, cut as shown in Figures 6 and 7. The prongs 9 are shortened just sufficiently to fit snugly within the shields 4 thus, together with the latter, forming a complete housing for the corner of the razor blade. The prongs 8 are preferably of such a length that when the razor is assembled the tips of the prongs will be in a line forming a tangent with the outer surface of the shields 4. The guard member is provided with two holes through which the studs 3 (if present) may extend when the razor is assembled. The handle 7 is hollow to receive the shaft 2.

15 The inside of the blade receiving member is given the proper curvature to give to the flexible blade, when assembled in the razor, an arcuate curvature as shown particularly in Figure 7. The upper face of the body portion 6 of the guard member has a similar curvature.

The blades 11 to be used with my improved razor are the standard Gillette type of thin flexible steel which can be obtained upon the market at a very small cost. The body portion 1 of the blade receiving member is shorter than the cutting edge of the blade 11 so that when the blade is positioned in the blade receiving member only a portion of the cutting edge of the blade is exposed, namely, that portion of the cutting edge which lies between the inner shoulders 5 formed by shields 4 with the body portion 1. The sharp objectionable corners of the blade 11 must, therefore, reside within and are entirely surrounded by the shields 4, so that when the razor is assembled and used for shaving, the skin will not be torn or cut by the sharp corners of the blade 11.

40 It is scarcely necessary to describe the assembling of my improved razor. The blade 11 is positioned in the blade receiving member, the studs 3 (if present) and the threaded shaft 2 passing through positioning holes that are provided in the blade. The guard member is then positioned upon the blade, the shaft 2 protruding into the handle 7 and the studs 3 protruding through positioning holes in the guard member. A cylindrical internally threaded member is provided for insertion in the handle to screw onto the shaft 2 and force the guard member against the blade thereby causing it to take the desired curvature for comfortable shaving.

45 It is, of course, possible to merely reduce the length of the four end prongs of the guard member of the standard Gillette type of safety razor so that it will fit into my improved blade receiving member. Thus by providing my improved blade receiving member with the standard Gillette type of safety razor, the guard member of which has been altered as above described, the user can

50 alternatively employ the set for shaving

smooth skin areas or depressed or concave skin areas.

It will be observed, therefore, that I have provided a safety razor which is easy to construct and maintain and which may be used to shave depressed or concave skin areas of the body, such as the arm pits without fear of injury from the corners of the razor blade. The fact of the matter is, it may be used with greater comfort upon smooth surfaces of the face and body than can the ordinary razor and my improved razor may, therefore, be said to be adapted to shave any part of the human body without fear of injury thereto.

I claim:

1. In a safety razor, a blade receiving member comprising a body portion shorter than the blade it is to receive and semi-cup shaped shields at the ends of said body portion and integral therewith, and a guard member having a plurality of prongs on either edge thereof, the end prongs being shorter than the others and being adapted to be housed in the said shields.

2. In a safety razor, a blade receiving member comprising a body portion with shoulders at the four corners thereof and a shaft member protruding from the center of the inner side of said body portion adapted to snugly receive the blade and guard member so as to position the blade and guard member against both longitudinal and lateral movement.

3. A blade receiving member for a safety razor comprising a body portion having semi-cup shaped shield portions at each end thereof for forming lather receptacles.

4. A blade receiving member for a safety razor comprising a body portion having extended shield portions at each end thereof recessed to receive the ends of a safety razor blade and semi-cup shaped to form lather receptacles.

5. A blade receiving member for a safety razor comprising a curved body portion which is shorter than the blade it is adapted to receive and which has extended shield portions at each end thereof recessed to house the ends of a blade received in said member and semi-cup shaped to form lather receptacles.

6. A safety razor in which the exposed cutting edge of the razor blade is less than its total cutting edge, the unexposed cutting edge being received in shield portions which are semi-cup shaped to form lather receptacles.

In testimony whereof I affix my signature.

ALBIN K. PETERSON.
